ROTARY PUMP VALVE CONSTRUCTION
FOR COMPRESSORS

Samuel Bousky, Shaker Heights, Ohio, assignor
to Jack & Heintz Precision Industries, Inc.,
Cleveland, Ohio, a corporation of Delaware

Application April 23, 1947, Serial No. 743,343

3 Claims. (Cl. 251—119)

1

This invention relates in general to check valves and has for one of its primary objects to provide a check valve of simplified and inexpensive construction and capable of efficient and foolproof performance at extremely high speeds.

Another object is to provide such a check valve that will have the desirable characteristics of a cantilever straight type but which by its shape and construction has a much reduced overall dimension and which is suitable for use in small standard recesses to valve standard passages.

Such a check valve has a particular utility in the circulation system for the refrigerant gas in a hermetically sealed motor compressor unit wherein sensitivity and positive action is highly essential under high speed operation.

With the foregoing and other objects in view, the invention resides in the combination of parts and in the details of construction hereinafter set forth in the following specification and appended claims, certain embodiments thereof being illustrated in the accompanying drawings, in which:

Figure 1 is a view of a motor compressor unit with part of the housing removed, showing the stator rotor and shaft in elevation and the end plates, compressor pump and check valves in longitudinal section;

Figure 2 is a view in cross section taken along line 2—2 of Figure 1 showing the compressor pump chamber and passages and leading thereto;

Figure 3 is a view in cross section taken along line 3—3 of Figure 1, showing passages leading from the compression chamber;

Figure 4 is an enlarged detail view in longitudinal section showing the improved check valve, with its limit stop, for the outlet passage from the compression chamber; and

Figure 5 is an enlarged view in top plan of the check valve shown in Figure 4 without the limit stop, and with anchoring means.

Referring more particularly to the drawings, the hermetically sealed motor compressor unit, which has been referred to as a particularly suitable device in which to use my new and novel check valve, may be of the same type disclosed in the co-pending application of Samuel Bousky for Compressor, Serial No. 743,342 filed April 23, 1947, now abandoned. The housing is shown at 1 enclosing a rotor 3 which rotates with a shaft 4 concentrically about a stator 2. The housing inlet is shown at 5 and the outlet at 6.

Between an upper end wall 7 and a lower end

5 wall 8 is disposed a rotary pump impeller 9 that is loosely mounted on an integral eccentric extension 10 of shaft 4 to rotate concentrically about shaft extension 10 but eccentrically in a compression chamber 11 between the impeller and the surrounding cylinder 13. In accordance with usual practice, a divider block 12 is positioned between the inlet to the compression chamber and the outlet therefrom and urged by 10 a spring 14 into the compression chamber and into constant contact with the impeller 9 to separate the inlet chamber from the outlet during the final portion of the compression stroke to insure the expelling of the compressed refrigerant gas through the outlet and prevent its re-expansion through the inlet.

The refrigerant vaporized in the evaporator, not shown, is fed through inlet 5 into a surging chamber 15 in the cylinder 13 and past a check valve 16 through a passage 17 into a compression chamber 11 on the inlet side of the divider block 12. After being compressed by the compressor in the compression chamber, the refrigerant gas passes through a passage 18 by a check valve, generally indicated in Figures 1 and 3, at 19, through a passage 20 into a surging chamber 21 in the upper end wall 7 and out through passage 22 into the compressor housing to be discharged therefrom through outlet 6.

It is of utmost importance that check valve 19 be highly efficient in readily permitting compressed refrigerant gas in the compression chamber to escape therethrough and preventing any flow back from the outlet back into the compression chamber regardless of the pressure conditions existing in the chamber. Therefore, a check valve of the construction shown in detail in Figures 4 and 5 is preferably employed. In order to accommodate a check valve for this purpose an easily machined round recess 27 is formed in the upper surface of the upper end wall 7 surrounding the passage 18 to be valved. Also immediately surrounding passage 18 is an insert 33 whose upper surface may be slightly higher than that of the bottom of the recess 27 as a matter of adjusting production tolerances to insure against the upper surface of insert 33 being lower than the bottom of recess 27 when the check valve is inserted for use.

As shown in Figures 4 and 5, the check valve itself is preferably of very thin springy metal to include a cut out rim portion 24 which is substantially circular to be accommodated in the circular recess 27. This rim portion has a pair of holes to receive bolts 26 to secure the same

to the upper end plate 7 in the bottom of recess 27. The rim 24 has integral therewith a valve leaf that extends towards the holes for the anchoring bolts 26 from the opposite side of the rim. This valve leaf 23 is round and enlarged and may be disposed at approximately the center of the rim. The resilient character of the check valve makes it so that when it is anchored by bolts 26 the valve leaf 23 is resiliently forced against the insert 33 to overlap passage 18 and normally resiliently close the same so as to function as an exhaust check valve. The check valve, being circular, is readily adaptable for use in the easily machined cavity 21. Another advantageous feature is the shape of the check valve itself wherein the sum effect of the rim 24 and valve leaf 23 has about the same resilience and valve action as that of a cantilever straight leaf type of valve but occupying a much smaller and more conveniently arranged space. The combination of mass and inherent resilience in the valve leaf itself is such as to permit a very high speed actuation and closure for while the valve must open and close during each revolution of the pump, the total time required for opening and closing actually occupies only between 15% and 30% of this total interval, depending upon operating pressures. Thus for a pump that makes one revolution in $\frac{1}{60}$ of a second the valve must open and close in .003 to .005 second on the average.

Above the valve leaf may be arranged a back stop comprising a separate, or integral, superimposed member 34 also anchored by screw bolts 26 and having a raised radially inwardly and angularly extending prong 25 which acts as a limit stop for the opening movements of the valve leaf 23. Also resting on the upper wall surrounding the recess 27 is a seal in the form of a dish shaped plate 29 having a portion 32 that extends into the recess 27 to seal the same. Another plate 30 is secured to the upper end wall 7 by a screw 28 and has an angular end 31 that rests against plate 32 to hold it in place. The prong 25 acts as a limit stop for the opening movements of the check valve piece 23. This construction permits the use of a very thin and lightweight check valve 23 which will be very sensitive so as to permit passage thereby of compressed refrigerant gas from the compression chamber. The novel limit stop construction not only limits the opening movement of the check valve but also prevents its destruction or warping under severe pressure conditions.

While a pair of screw bolts 26 have been described and shown as suitable anchoring means for the check valve and back stop, it should be understood that other anchoring means may be employed if desired, the important feature being that the flexure of the valve rim portion opposite the valve leaf 23 be restricted, leaving the valve leaf 23 free to open in response to discharge impulses through passage 18 sufficient to overcome the resilient closure thereof. As previously stated the backstop may take forms other than that actually shown, the important feature being that it acts as a limit stop to prevent excessive opening movements of the valve leaf 23.

I claim:

1. A check valve comprising a substantially 70

5 circular thin flat spring metal rim portion disposed concentrically with respect to the passage to be valved, said rim portion having a valve leaf of thin flat spring metal extending radially inwardly and terminating in an enlarged portion adapted to resiliently contact in overlapping relationship the passage to normally maintain the latter closed under the effect of the inherent springy characteristics of said check valve, anchoring means for anchoring only that part of the rim portion opposite the inner radially extending end of said valve leaf, leaving said valve leaf and the remaining part of said rim portion free to flex with respect to said anchoring means and a limit stop means for limiting excessive opening movements of said valve leaf, said limit stop being anchored by said anchoring means and having a member superimposed in normally spaced position above said valve leaf.

10 2. A reed valve and a passage to be valved thereby, said valve being comprised of flat resilient material having an annular portion and a re-entrant radially inwardly extending central flap section, anchoring means for anchoring a part 15 of said annular portion to dispose said annular portion concentrically with the passage to be valved and to normally dispose said central flap section in overlapping contact with said passage to close the same and so that the remainder of 20 said annular flap portion is free to flex with respect to said anchoring means.

25 3. A reed valve and a passage to be valved thereby, said valve being comprised of flat resilient material having an annular portion and a re-entrant radially inwardly extending central flap section, anchoring means for said annular portion to dispose said annular portion concentrically with the passage to be valved and to normally dispose said central flap section in 30 overlapping contact with said passage to close the same, said anchoring means being adapted to anchor only a portion of the rim of the annular portion opposite the re-entrant central flap section and being otherwise disassociated with said central flap section so that the central flap section and the remainder of said rim portion are free to flex with respect to said anchoring means.
